DES. 2064

Clark Strong, of Chatham Conn.

Letters Patent 182064 Dated May 9, 1865

Design for a Coffin Handle

The schedule referred to in these Letters Patent and making part of the same.

To all whom it may concern:

Be it known that G. Clark Strong, of the
Town of Chatham, in the County of Middlesex and State of Connecticut,
but, have invented or produced a new and original design for a
military or patriotic Coffin Handle; and I do hereby declare that
the following is a full and exact description of the same, reference
being had to the accompanying drawing.

In my design I use the United States shield for ease
to ornament and support the handle proper.

It is necessary for each handle ear to have a pro-
jection to form a socket for the handle to work in I have faced said
socket with small shield sufficient to cover its front, so as to preserve
the military effect of the design. (See diagram, hanging drawing).

To be true to nature I have set silver white stars on a dark
or polished ground.

What I claim as my invention or production is, The de-
sign for a coffin handle as shown and described.
